UNITED STATES PATENT OFFICE.

ADOLPH JAEGER, OF BREMERHAVEN, GERMANY.

FOG-HORN.

SPECIFICATION forming part of Letters Patent No. 229,044, dated June 22, 1880.

Application filed February 16, 1880.

To all whom it may concern:

Be it known that I, ADOLPH JAEGER, resident of Bremerhaven, Empire of Germany, have invented new and useful Improvements 5 on Fog-Horns, of which the following is a specification.

The object of my invention is to devise means to permit the use of fog-horns operated by steam on sailing-vessels, which have heretofore been deprived of this valuable signaling-instrument, owing to the lack of means for generating the necessary steam to operate the fog-horn; and to that end the invention consists, first, in the combination, with a fog-horn, 15 of a portable steam generator or boiler adapted to be heated either by the fire of the galley range or stove or by fire in a separate small stove or furnace; secondly, in the combination, with said fog-horn and steam-generator, 20 of a feed-water tank, as fully described hereinafter, and shown by the accompanying drawing, which illustrates the invention by a vertical elevation, partly in section, of the apparatus.

25 A is a cylindrical or otherwise shaped vessel, made of strong sheet metal and provided with an annular projecting flange or rim, a, to adapt said vessel to be set into one of the holes of a galley range or stove or other like 30 heating apparatus, and in which vessel the steam required for operating the fog-horn is generated. It is provided with a manometer, a', a safety-valve, a'', and a try-cock, a''', which latter may be employed to draw off hot 35 water for culinary or other purposes when the generator A is not employed to operate the fog-horn.

B is a feed-water tank of any desired capacity, connected with the generator A by a pipe, 40 b, provided with a stop-cock, b', located at or near the upper end of the feed-tank, and by a pipe, b'', having a stop-cock, b''', located at or near the lower end of said feed-tank, which is further provided with a feed-funnel, C, connected with the top of the tank B by means 45 of a short pipe, c, having a stop-cock, c'.

In practice I employ a feed-tank of sufficient capacity to feed the boiler or generator with the necessary water for operating the 50 fog-horn for one hour.

When the boiler is to be fed the stop-cock

c', as well as the stop-cock b''', is opened, and the necessary quantity of water is allowed to flow into the generator A, and the stop-cock b''' is then closed and the feed-tank B replenished 55 with water. If the generator is to be supplied with water after steam has been generated the stop-cock c' is closed, and those b' b''' opened. Steam rushing into the tank B will force the water through pipe b'' into the generator. 60

D is a steam-pipe leading to the fog-horn E. It is provided with a three-way cock, d, so that the steam from the generator may be conducted either to the fog-horn or to the blow-off or waste pipe d', with which connects 65 the pipe d'', having a stop-cock, d''', which latter pipe may be employed to conduct the steam into the various cooking-vessels of the range, to be employed for culinary purposes or for other purposes when not employed to operate the fog-horn. 70

E is the fog-horn, constructed in the usual way, the sound-producing device being somewhat similar to those in wind or tongue or reed instruments, and consisting of a strong metallic 75 spring fitting accurately over a slit of a width equal to the spring e, the sound being produced by the action of the steam upon said tongue when rushing through the slit.

Those conversant with the art of constructing wind-instruments are aware that any variation in the direction of the air will considerably modify the pitch of the sound emitted by the usual sound-producing devices. By applying the resonant diaphragm above these sound-producing devices to change the direction of the steam rushing through the slit the sound is greatly increased in pitch, while the concave shape adopted will increase the volume of the sound. 80

In practice I prefer to construct the sound-duct of the fog-horn on the principle of the ordinary speaking-trumpets, having found by experience that better results can be obtained, considering the amount of power obtainable 85 from so small a generator, than when the fog-horn is constructed in the usual way; and to still further increase this power I employ what I may term a "sound-catcher," which is a vibrating inverted cup-shaped spring, F, applied immediately above the reed or other primary sound-producing device to catch, as 90 100

it were, the sound and steam or produce a secondary increased volume of sound, that is then emitted by the horn. It will, however, be understood that I do not limit myself to any particular size of generator or to any particular construction of fog-horn, as these may be varied according to the furnace or galley upon which they are employed.

Having now described my invention, what I claim, and desire to secure by Letters Patent, is—

1. In conjunction with a galley stove or range of a sailing-vessel, a portable steam-operated fog-horn, combined with a steam-tight boiler having a steam-feeder, and a three-way blow-off cock interposed between said boiler and fog-horn, substantially as described, for the purposes specified.

2. In conjunction with a galley stove or range of a sailing-vessel, a portable and steam-operated fog-horn, combined with a steam-tight boiler having a steam-feeder and a try-cock, and the three-way blow-off cock interposed between said boiler and fog-horn, provided with a pipe attachment for separate use, all arranged to operate substantially as described, for the purposes specified.

In witness that I claim the foregoing I have hereunto set my hand and seal this 24th day of December, 1879.

ADOLPH JAEGER. [L. S.]
